CLAIM

The ornamental design for a lid with infuser, as shown and described.

DESCRIPTION

FIG. 1 is a rear, top, right perspective view of a lid with infuser showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a partial view of a portion of FIG. 7.

The evenly-spaced broken lines in the Figures are for the purpose of illustrating portions of the lid with infuser and form no part of the claimed design.

The dash-dot broken lines of FIG. 7 is included to show a partially enlarged view only and forms no part of the claimed design.
